Dec. 429

W. Ames, of Nashua, N.H.
assignor to
J. Haatshorn & W. Ames.
Letters Patent No. 429. Dated Dec. 9. 1857.

The schedule referred to in these Letters Patent & making part of the same.

To all Persons to whom these Presents shall come:

Be it known

that I, Winslow Ames, of Nashua, in the County of Hillsborough, and state of New Hampshire, have invented or produced a new and useful design for a stove, and I do hereby declare that the same is described & represented in the following specification and, accompanying drawings, letters, figures and references thereof.

Of the said drawings figure 1, denotes a view of the top plate of the stove.

Figure 2, is a view or elevation of one of the side plates, together with the top & bottom plates.

Figure 3, is an elevation of one of the end plates & top & bottom plates.

Figure 4, is a vertical section of the side plate taken on the red line a, b, of figure 2.

Figure 5, is a vertical & central section of the end plate.

Figure 6, a cross section of the top plate.

The principal design constituting my production is shewn either on the side or end of the stove, it being separate from that of the water urn which is shewn as resting on the top plate.

The said design consists of the ornamental semi star and rays & mouldings of the end or side of the top plate (as seen in the drawings) the circular ornament A, and four or more surrounding ornaments B, C, D, E, together with the mouldings of the top & bottom plate, all essentially as re-

presented in either of the side or end views and their sections & such ornamental design substantially as exhibited in the above mentioned drawings, I claim as my invention or production and I also claim the ornamental design or configuration of the water now as shown in figures 1, 2 and 3.

In testimony whereof, I have hereto set my signature this twelfth day of November A.D. 1857.
